UNITED STATES PATENT OFFICE.

GEORGE W. KRAMER, OF LITTLE ROCK, ARKANSAS, ASSIGNOR TO KRAMER AUTOMATIC TAMPER CO., OF PEORIA, ILLINOIS, A CORPORATION OF ILLINOIS.

MACHINE FOR MAKING CONCRETE BUILDING-BLOCKS.

981,928.

Specification of Letters Patent. Patented Jan. 17, 1911.

Application filed September 4, 1906. Serial No. 333,067.

To all whom it may concern:

Be it known that I, GEORGE W. KRAMER, a citizen of the United States, residing at Little Rock, in the county of Pulaski and State of Arkansas, have invented certain new and useful Improvements in Machines for Making Concrete Building-Blocks; and I do hereby declare that the following is a full, clear, and exact description of the invention, which will enable others skilled in the art to which it appertains to make and use the same.

This invention has reference more particularly to apparatus for packing concrete into molds for forming concrete building blocks or stone, and for supplying concrete to the mold.

The object of my invention is to provide a machine that will thoroughly tamp the concrete and press it into all parts of the mold;—and a further object is to supply concrete to the mold in suitable quantities to be thoroughly pressed into the mold by the tamping device.

In the accompanying drawings, in which similar reference characters indicate similar parts in the several views, Figure 1 is a front view of a machine embodying my improvements showing the tamping devices in operation; Fig. 2 a vertical cross sectional view on the line 2—2 of Fig. 1 looking in the direction indicated by the arrow; Fig. 3 a front view of the machine showing the tamping devices raised to the inoperative position; Fig. 4 a vertical sectional view of the mold and feeding devices which supply concrete to the mold; Fig. 5 a vertical sectional view on the line 5—5 of Fig. 1 looking in the direction indicated by the arrow; Fig. 6 a view on the line 6—6 of Fig. 5 looking as indicated by the arrow; Fig. 7 a view on the line 7—7 of Fig. 3 looking as indicated by the arrow; Fig. 8 a view on the line 8—8 of Fig. 3 looking as indicated by the arrow showing a bottom view of the tamper; and Fig. 9 is a side and bottom view of a tamper which may be used for tamping the concrete block of different construction from that shown in the preceding figures.

The frame of this machine, which is constructed and braced to withstand considerable vibration is provided with two pairs of vertical timbers 1, each pair being suitably spaced to furnish a guide way for the frame 2, which travels therebetween. These tim-

bers 1 are suitably connected at their top and to the adjacent framework 3 upon which are carried parts which operate the tamping devices.

The frame 2 which carries the tamping devices and which as has been stated, is vertically movable in the pairs of vertical timbers 1 consists of the blocks 4 which are suitably distanced and have the parallel strips 5 secured thereon, as shown, near the top and bottom thereof which extend beyond said blocks and engage the vertical timbers 1. These strips 5 are provided with the connecting strips 6 which engage the inner sides of the timbers 1 so as to prevent longitudinal shifting of the said frame and permit vertical movement thereof. This framework is designed to carry the tamping devices which operate to tamp the concrete into the mold 7 located directly underneath, which said mold may be of any desired construction.

As is shown, the concrete blocks are usually cored as shown at 8 Fig. 3 of the drawings, by providing the cores 9 which may be arranged in any suitable manner or operated so as to extend in the mold so as to provide the concrete block formed therein with suitable openings. In the accompanying drawings, I have shown a mold which is provided with five cores 9 which extend vertically in the mold and are spaced an equal distance apart throughout the length of the mold.

The tamping device carried by the movable frame 2 comprises a shaft 10 which extends horizontally through said frame and is journaled in the bearings 11 secured to the blocks 4. Upon this shaft are provided six eccentric disks 12 which are preferably arranged at thirty degree intervals around the shaft so that the projection of the said disks will be distributed throughout the revolution of the shaft. These eccentric disks are provided with the usual yokes 13 encircling the same which are pivotally connected by means of the short shafts 14 as at 15 with the cross heads 16. These cross heads are arranged to be vertically movable and extend from side to side of the frame 2 and are provided with the arms 17 extending laterally from said cross heads, through which said projecting parts are passed the rods 18, which are secured against movement by the set screws 19 or any other suitable means. The ends of these rods pass 110

2 through openings in the strips 5 so as to guide the cross head accurately in its vertical reciprocation, and said rods are carried by the laterally projecting arms 17 at the side as aforesaid so as to be out of the plane of movement of the eccentrics 12. The cross heads 16 are provided with the depending parts 20 which are bored at their lower ends to receive the shank of the tamping bars 21 which are secured therein by means of set screws or in any other desired manner. These tamping bars are arranged to operate in the mold located therebeneath and differ in form according to the size of the mold and the kind of core used therein. The striking faces of the tamping bars, irrespective of the size or form, have the edges beveled as shown at 24 to diminish the abrupt striking surface thereof to permit the hammer being driven into the loose concrete, and also to provide inclined or beveled faces for forcing the concrete laterally from the line of direction of the movement of the tamping bars into all parts of the mold.

It is necessary that the lower surface of the tamping bars be capable of operating in the interior of the mold near the bottom thereof so as to press the concrete into the bottom of the mold, and for this reason the tamping bars are cut away to avoid the cores in the mold and provide projecting portions which may extend intermediate of the cores and walls of the mold to the bottom of the mold. In the present instance, wherein a number of small vertical rectangular cores are used, the tamping bars are constructed as shown in Fig. 8 so that the portion 23 operates between the cores and the portions 24 intermediate of the cores and walls of the mold, the said portions 24 extending laterally a suitable distance so as to operate in close proximity to the adjacent tamping bars so as to subject all the concrete in the mold to the pounding thereof. As is apparent, it is necessary that the tamping devices be capable of vertical movement during operation so that as the mold fills and the concrete is packed therein the tamping device may rise, and it is also necessary that they be adapted to be raised from the mold when not in operation. For this purpose, there is provided a drive shaft 25 extending longitudinally across the top of the frame which carries the sleeve or drum 26 loosely thereon directly above the frame 2. This frame is connected to the said sleeve by means of the wire cables 27 or any other suitable flexible means which are connected with the sleeve or drum 26 so as to wrap and unwrap thereon in the movement of said sleeve for raising and lowering the movable frame.

For operating the sleeve 26, there is provided at one end thereof a friction disk 28

which is fixed on the shaft 25 and adapted to engage the broad end of the sleeve. At the opposite end of said sleeve is provided a friction disk 29 which is movable lengthwise of said shaft, the said disk being feathered on the said shaft to cause the said disk to rotate with the shaft. Adjacent the loose friction disk 29 and secured on the shaft 25 is a collar 30, and an inverted bifurcated wedge member 31 is carried between said collar 30 and the friction disk 29, the prongs of which said wedge member straddle the shaft and are arranged when forced downwardly to bear against the collar 30 and press the friction disk 29 against the large end of the sleeve or drum 26 so as to lock the sleeve between the friction disks 28 and 29 to rotate with the shaft. This wedge member 31 is carried on the rod 32 which is pivoted on the bracket 33 on one side of the frame, and the other end of said rod extends to the opposite side of the frame where it is connected by means of the link 34, the pivoted lever 35 and rod 36 with the foot lever 37, whereby the operator at the front of the machine can control the operation of the coiling sleeve. The arms or prongs of this wedge converge downwardly so that the friction clutch is thrown into engagement by the downward movement thereof and the spring 38 is provided, which is connected near the free end of the lever 37 and to the supporting frame so as to normally draw the wedge 31 downwardly and lock the sleeve 26 to move with the shaft. By means of the wedge applied as hereinbefore described, the sleeve is caused to be impinged to cause it to be revolved with the drive shaft to raise the movable frame, and then the wedge is moved to release such impingement but instead of entirely releasing said impingement, as the movable frame descends the operator allows a slight impingement, sufficient to retard the downward movement of the movable frame to prevent its descending violently.

On the outer end of the shaft 25 is loosely mounted a pulley which is driven by the belt 39 and said pulley is provided with a sleeve 40 which has a clutch lug thereon adapted to engage the fixed clutch member 41 on the shaft 25, and the sleeve 40 on the pulley is further provided with a pair of annular flanges 42 suitably distanced to receive the end of the short arm 43 of a shifting lever which is pivoted to a bracket 44 on the frame, for shifting the clutch of the belt pulley in and out of engagement with the clutch 41 on the shaft, and the pulley is driven in a direction to operate the shaft to wind the cable 27 on the sleeve 25.

The long arm 45 of the shifting lever extends as shown and is arranged to be engaged by the projection shown by dotted lines at 46 carried on the strip 5 of the mov-

able frame 2 and projecting inwardly therefrom so that as said movable frame nears the limit of its upward movement, said projection strikes the end of the long arm 45, raises it and throws the pulley out of engagement with the clutch 41 and prevents further raising of the frame 2. To hold the movable frame in its elevated position, the wedge 31 is held normally downwardly by the spring 38 which holds sleeve 26 from turning upon shaft 25 and shaft 25 is held from turning by the friction of the parts comprising the tampers and their operative connections with said shaft. If desired, an ordinary ratchet and pawl may be applied in operative relation with the shaft and frame to insure shaft 25 from being turned by the weight of the movable frame when said shaft has been freed from its driving connection when the movable frame is in its most elevated position. However, in practice, it has not been found necessary to supply the ratchet and pawl as the friction of the parts has been found amply sufficient to overbalance the weight of the movable frame. When the operator presses the lever 37, however, the wedge is raised, the sleeve 26 allowed to turn independent of the shaft 25 and the frame 2 drops by reason of its own weight and drives the tampers of the tamping mechanism into the loose concrete in the mold. For operating the shaft 10 in every position of its vertical movement, there is provided a tubular member 47 which has a universal joint connection as at 48 with the end of the shaft 10 and said tube telescopes the rod 49 which said rod has a universal joint connection as at 50 with a sprocket 51 which is driven by means of the chain 52 from the sprocket 53 on the shaft 25. The tube 47 is provided with the longitudinal slots 54 diagonally arranged therein, through which extends the key 55 which passes through the rod 49 and the slots 54 are of sufficient length to permit considerable longitudinal movement of the key 55 therein to permit the required extension of the shaft when the frame 2 is raised to the inoperative position as shown in Fig. 3.

For feeding concrete to the mold, there is provided a hopper 56 which is kept constantly supplied with prepared concrete from any desired source and a shiftable section is arranged to receive a supply of concrete from said hopper and carry it to and deposit it in the mold. This shiftable section which is indicated at 57 has a compartment 58 therein which is open at the top and the bottom and of the same horizontal dimensions as the mold which it is designed to supply. This section is carried by a table 59 and arranged to shift horizontally from the position in which the opening therethrough registers with the opening in the mold as shown in Figs. 2 and 4, rearwardly to a posi-

tion in which it registers with the spout 60 of the hopper 56, the mouth of the spout being also of the same horizontal dimensions as the compartment in the section 57. This section is held between the spout 60 of the hopper and the table 59 and mold box 7 and is guided in its to and fro movement by the cleats 61 on the table, and the said section is provided with a platform 62 which when the said section is moved to register with the mold box, covers and closes the outlet from the mouth 60 of the hopper, and the surface of the table provides a bottom for the compartment 38 in the section when it is moved to register with the mouth of the hopper.

In the operation of my machine, the section 57 is moved rearwardly and receives a charge of concrete from the hopper 56. The section is then drawn forward by means of the handles 63 which movement carries the platform thereon under the mouth of the hopper and closes the same and as the said section is moved to register with the mold box, the concrete therein falls down into said box. The operator, then, while the section 57 is still in the forward position registering with the opening in the top of the mold, depresses the lever 37 which, in the manner hereinbefore set out, releases the frame 2 and allows it to fall under its own weight to drive the hammers 21 down into the loose concrete in the mold in the falling movement thereof. The downward movement of the frame 2 moves the projection 46 away from the long arm 45 of the shifting lever and allows said arm to drop under its own weight, which throws the clutch of the pulley into engagement with the clutch 41 on the shaft 25 and causes the shaft to rotate, driving the sprocket 51 and shaft 10 which operates the bars 21 of the tamping devices, so that as the tampers strike the concrete in the mold, they are rapidly reciprocating. The eccentrics are arranged on the shaft 10 to drive the tampers in rapid succession and the tampers, under the weight of the frame and the tamping mechanism thereon operate in the loose concrete in the mold, packing the concrete down into the mold and wedging it sidewise by means of the faces 64 into all parts of the mold into a hard mass, and as the concrete is packed under the blows of the tampers the tampers with the movable frame gradually rise as the loose concrete is gradually pressed in place, and lift the frame 2. The operator is able to vary the force of the blow by varying the pressure on the lever 37 and operating the wedge 31 to cause the friction clutch to grip the sleeve 26 more or less and cause the sleeve to carry more or less of the weight of the frame 2 and reduce the force of the blow of the tampers on the concrete. The operator holds the lever 37 down and allows the tamping devices to operate until the

complete charge of concrete is packed solidly in the mold when he releases the pressure on the lever, allows the spring 38 to force the wedge 31 into operation which causes the movement of the shaft 25 to elevate the movable frame 2.

In the elevation of the movable frame, the long arm 45 of the shifting lever is raised, the pulley thrown out of engagement with the shaft, the shaft ceases to turn and the tamping devices to operate. The section 57, the compartment of which is designed to hold a little more than half enough concrete to fill the mold, is then moved back and receives a charge of concrete from the magazine and is then moved forward and discharged into the mold, and the tamping devices brought into operation as before described. As the supply of concrete is more than sufficient to fill the mold, a portion of it will extend above the top of the mold and be tamped solidly in the compartment of the section 57. When the block is tamped sufficiently, the tamping devices are raised to the inoperative position, as before described, and the section 57 moved back to register with the discharge opening of the hopper in which movement the edge of the front of the compartment shears off the surplus concrete extending above the mold, making the top of the block perfectly level and insuring a construction of blocks of uniform thickness.

While I have shown a mold for constructing concrete blocks of a certain form and style, I wish it understood that any suitable concrete block mold may be used. When molds adapted to form blocks of different styles are employed the tampers 21 which, as has been hereinbefore mentioned, are detachable, are detached and tampers suitable for that style of mold attached to the arms of the cross heads. For instance, when a mold is employed which forms concrete blocks with long openings as shown by dotted lines at 65 in Fig. 3, it will be necessary at place to provide tampers such as shown in Fig. 9 to straddle the core and tamp the concrete on each side thereof. The various other kinds of cores which are commonly employed in constructing these blocks will require tampers varying in shape for tamping the concrete around said cores.

What I claim is:

1. In a device of the class described, the combination of a constantly driven part, a stationary frame provided with driven shaft therein adapted to be intermittently driven from the constantly driven part, a movable frame carrying a rotative shaft, a series of tamping members, means upon the shaft of the stationary frame intermittently revoluble therewith, and means connecting said intermittently revoluble means with the movable frame to raise the movable frame,

means under the control of the operator for causing intermittent engagement and release between the revoluble means and the shaft and the same means similarly controlled for retarding the gravity descent of the movable frame, means connecting the shaft of the stationary frame with the shaft of the movable frame comprising parts relatively adjustable to compensate for the varying distances between the shaft of the stationary frame and the shaft of the movable frame during the movement of said movable frame, whereby the tampers connected with the shaft of the movable frame may be reciprocated and means operable through the upward movement of the movable frame to disconnect the drive shaft from the constantly driven part whereby the movement of said shaft will be stopped when the movable frame is in its maximum elevated position.

2. In a device of the class described, the combination of a constantly driven part, a stationary frame provided with a horizontally disposed drive shaft therein adapted to be intermittently driven from the constantly driven part, a vertically movable frame carrying a rotative shaft, a series of tamping members, means for connecting the tamping members with the rotative shaft in a manner to permit them to be reciprocated with the rotation of said shaft, means upon the shaft of the stationary frame intermittently revoluble therewith and flexible means connecting the said intermittently revoluble means with the movable frame to facilitate the raising and lowering of the latter, means under the control of the operator for causing intermittent friction engagement between the revoluble means and the shaft and means similarly controlled for frictionally retarding the downward movement of the movable frame, means connecting the shaft of the stationary frame with the shaft of the movable frame comprising parts relatively adjustable to compensate for the varying distances between the shaft of the stationary frame and the shaft of the movable frame during the movement of said movable frame, whereby the tampers connected with the shaft of the movable frame may be reciprocated, and means operable through the upward movement of the movable frame to disconnect the drive shaft from the constantly driven part whereby the movement of said shaft will be stopped when the movable frame is in its maximum elevated position.

3. In a device of the class described, the combination of a main supporting frame, a driven shaft therein, a vertically movable frame provided with reciprocal tamping members, means for reciprocating said tamping members from the drive shaft, means associated with said movable frame

and drive shaft in such relation that the former may be intermittently connected with the latter to be raised thereby, means under the control of the operator to cause such raising connection between the movable frame and the drive shaft, and the same means similarly controlled to frictionally retard the gravity descent of the movable frame when released from its connection 10 with the drive shaft to cause said movable frame to descend at uniform speed.

4. In a device of the class described, the combination of a stationary frame, a drive shaft therein, a vertically movable frame 15 carried in the stationary frame provided with tamping members, means for operating the tamping members from the drive shaft, means for intermittently connecting the movable frame and the drive shaft in a relation 20 to cause the former to be raised through the turning of the latter and when disconnected the movable frame will descend by force of gravity, means under the control of the operator for causing intermittent engagement and release of the connecting 25 means between the drive shaft and movable frame, and the same means similarly controlled to frictionally retard the gravity descent of the movable frame to cause it to descend at a uniform speed.

5. In a device of the class described, the combination with the main supporting frame provided with a driven shaft, and a vertically movable frame supported therein provided with guide rods for tamping bars, a revoluble shaft in the movable frame, an eccentrically supported series of tampers carried thereon, an intermittently frictionally driven part upon the shaft of the main frame, flexible means connecting the movable frame with the intermittently driven part on the drive shaft adapted to be coiled up or uncoiled through the movement of the shaft in the main frame to facilitate the raising and lowering of the movable frame, means upon the drive shaft under the control of the operator to cause the intermittently driven part on the drive shaft to be engaged with the latter to be turned therewith and the same means similarly controlled to cause a slight engagement between said parts during the descent of the movable frame to retard the downward movement of the movable frame, and means connecting said shaft of the main frame with the shaft of the movable frame to cause the tampers to be operated.

6. In a device of the class described, the combination with the main supporting frame provided with a driven shaft, and a vertically movable frame supported therein provided with guides for tamping bars thereon, suitably placed to engage said tamping bars and guide them, a revoluble shaft in the movable frame, an eccentrically sup-

ported series of tampers carried thereon, an intermittently frictionally driven part upon the shaft of the main frame, provided with a disk thereon, flexible means connecting the movable frame with the intermittently driven part adapted to be coiled up or uncoiled through the movement of the intermittently driven part to facilitate the raising and lowering of the movable frame, a disk upon the drive shaft movable longitudinally thereof and means under the control of the operator for moving said movable disk to cause the intermittently driven part to be engaged with the shaft to cause it to be turned therewith to raise the movable frame 80 and the same means similarly controlled to cause a slight engagement between the movable disk and the sleeve during the descent of the movable frame to retard its movement, and means connecting said shaft of the main frame with the shaft of the movable frame to cause the tampers to be operated.

7. The combination of a stationary frame, a drive shaft therein, a movable frame, a shaft therein carrying a series of tampers, means for operating said tampers from the drive shaft, a sleeve on the drive shaft intermittently revoluble thereby, flexible means connecting said sleeve with the movable frame, means under the control of the operator for causing the sleeve to be intermittently frictionally driven from the drive shaft to raise the movable frame and to be disengaged to allow the movable frame to descend by force of gravity, and the same means similarly controlled to frictionally retard the movement of the sleeve as it is turned by the weight of the movable frame as it descends to cause it to descend at substantially uniform speed.

8. The combination with a stationary frame having a drive shaft therein provided with a pair of disks one fixed and the other, movable thereon, of a movable frame carrying a series of tampers, a horizontally disposed shaft in the movable frame, means connecting the shaft of the movable frame with the tamping members in a relation that when driven the tampers will be reciprocated, means for driving the shaft of the movable frame from the drive shaft of the stationary frame; means to facilitate the raising and lowering of the movable frame comprising a sleeve on the drive shaft intermittently revoluble thereby, flexible means connecting said sleeve with the movable frame and including a movable part on the drive shaft, under the control of the operator, for causing said sleeve to be intermittently engaged by the movable part on the drive shaft to cause it to be turned with the latter to raise the movable frame, and the same means similarly controlled to retard the movement of the sleeve as it is turned by

the weight of the movable frame as it descends.

9. The combination with a stationary frame having a drive shaft therein provided with a pair of disks, one fixed and the other movable thereon, of a movable frame carrying a series of tampers, means for operating said tampers including the said drive shaft, a horizontally disposed shaft in the movable frame connected with the drive shaft by a connection comprising parts shiftable relatively to compensate for the varying distances between the drive shaft and the shaft of the movable frame, means to facilitate the raising and lowering of the movable frame comprising a sleeve on the drive shaft intermittently revoluble thereby, flexible means connecting said sleeve with the movable frame, and means under the control of the operator for causing said sleeve to be intermittently engaged by the disks on the drive shaft and the same means similarly controlled to retard the movement of the sleeve as it is turned by the weight of the movable frame as it descends.

10. The combination with a stationary frame having drive shaft thereon provided with friction disks, of a movable frame carrying a series of tampers, means for operating said tampers including the said drive shaft, a horizontally disposed shaft in the movable frame connected with the drive shaft, means to facilitate the raising of the movable frame comprising a sleeve on the drive shaft intermittently revoluble thereby, flexible means connecting said sleeve with the movable frame, and means under the control of the operator for causing said sleeve to be intermittently engaged by the disks on the drive shaft to cause the sleeve to be turned to raise the movable frame and the same means similarly controlled to slightly impinge said disks to retard the movement of the sleeve when it is freed from engagement with the drive shaft to prevent the movable frame from descending too rapidly.

11. The combination with a stationary frame having a drive shaft thereon provided with a pair of disks, one fixed and one adjustable thereon, a movable frame carrying a series of tampers, means for operating said tampers, including said drive shaft, a horizontally disposed shaft in the movable frame connected with the drive shaft, means to facilitate the raising of the movable frame comprising a sleeve on the drive shaft, intermittently revoluble thereby, flexible means connecting said sleeve with the movable frame, and means under the control of the operator for causing said sleeve to be intermittently engaged by the disks on the drive shaft, and the same means similarly controlled to facilitate the lowering of the movable frame, including the fixed and movable

disks on the drive shaft, and further comprising a fixed collar upon the drive shaft and a wedge movable under the control of the operator to be inserted and withdrawn between the fixed part on the drive shaft and the movable disk thereon, whereby the movable frame may be retarded in its descent. 70

12. The combination of a stationary frame and a frame vertically movable therein carrying tamping members, means for operating the tampers comprising a horizontally disposed shaft in the tamper frame, a driven shaft in the stationary frame, a part upon the stationary frame, driven from the drive shaft and a bar comprising relatively 80 movable parts, one end connected with the driven part on the stationary frame and the other end with the tamper driving shaft in the movable frame, means for raising and lowering the movable frame comprising a 85 sleeve upon the drive shaft, a rope or chain connecting the sleeve with the movable frame, means on the drive shaft under the control of the operator for causing intermittent engagement of the sleeve with the drive 90 shaft to cause the former to be turned with the latter in raising the movable frame, and the same means similarly controlled to frictionally retard the movement of the sleeve in the descent of the movable frame. 95

13. The combination of a stationary frame, a mold fixed relatively thereto, a movable frame carrying a series of reciprocal tampers, means for operating the tampers, comprising a horizontally disposed shaft 100 in the movable frame, a driven shaft in the stationary frame, a bar comprising relatively movable parts, one end suitably connected to be driven from the drive shaft and the other end connected with the shaft in the 105 movable frame, means for raising and lowering the movable frame comprising a sleeve upon the drive shaft, a rope or chain connecting the sleeve with the movable frame, means on the drive shaft under the control 110 of the operator for causing intermittent engagement of the sleeve with the drive shaft to cause the former to be turned with the latter in raising the movable frame, and the same means similarly controlled to frictionally retard the movement of the sleeve in the descent of the movable frame. 115

14. In a device of the class described, the combination with a stationary frame provided with a drive shaft therein, of a vertically movable frame provided with a shaft therein supporting a series of tampers eccentrically associated with said shaft in the movable frame, guides in said movable frame for said tampers, means for operating the tampers including the drive shaft in the main frame and the shaft in the movable frame, driven means between the two shafts comprising parts adjustably related, means 125 for raising and lowering the movable frame 130

comprising a sleeve on the drive shaft, a rope or chain connecting the sleeve with the movable frame means including a movable part on the drive shaft under the control of the operator for causing said sleeve to be intermittently turned with the drive shaft to raise the movable frame, and the same means similarly controlled to retard the movement of the sleeve as it is turned by the weight of the movable frame as it descends.

15. In a device of the class described, the combination with a stationary frame provided with a drive shaft therein, of a vertically movable frame provided with a shaft therein supporting a series of tampers eccentrically associated with said shaft in the movable frame, guides in said movable frame for said tampers, means for operating the tampers including the drive shaft in the main frame and the shaft in the movable frame, driven means between the two shafts comprising parts movable relatively to accommodate the varying distance between the drive shaft and the shaft of the movable frame in the movement of said frame within the stationary frame, means for raising and lowering the movable frame comprising a sleeve on the drive shaft, disks 30 non-rotatively engaging the drive shaft a rope or chain connecting the sleeve with the movable frame and means including a movable part on the drive shaft, under the control of the operator, for causing said sleeve to be intermittently engaged by the disks 35 on the drive shaft to cause it to be turned with the latter to raise the movable frame, and the same means similarly controlled to retard the movement of the sleeve as it is turned by the weight of the movable frame as it descends.

16. In a device of the class described, the combination with a stationary frame provided with a drive shaft therein, of a vertically movable frame provided with a shaft therein supporting a series of tampers eccentrically associated with said shaft in the movable frame, guides in said movable frame for said tampers, means for operating the tampers including the drive shaft in the main frame and the shaft in the movable frame, driven means between the two shafts comprising parts movable relatively to accommodate the varying distance between the drive shaft and the shaft of the movable frame in the movement of said frame within the stationary frame, means for raising and lowering the movable frame comprising a sleeve on the drive shaft, disks non-rotatively engaging the drive shaft a rope or chain connecting the sleeve with the movable frame means including a movable part on the drive shaft, under the control of the operator, for causing said sleeve to be intermittently engaged by the disks on the

drive shaft to cause it to be turned with the latter to raise the movable frame, and the same means similarly controlled to retard the movement of the sleeve as it is turned by the weight of the movable frame as it descends.

17. In a device of the class described, the combination of a stationary frame, a mold fixed relatively thereto, a vertically movable frame supported in said stationary frame, tamping means within the vertically movable frame operable within the mold under the weight of the movable frame including their own weight comprising a horizontally disposed shaft provided with a plurality of eccentricities thereon set at different angles relatively, a plurality of vertically disposed tamping bars having yokes embracing the eccentricities on the shaft, means for operating the tamping mechanism from the drive shaft, driven means between the two shafts comprising parts movable relatively to compensate for the varying distance between the drive shaft and the shaft of the movable frame in the operation of the tampers within the mold, means for raising and lowering the movable frame comprising a sleeve on the drive shaft, a rope or chain connecting the sleeve with the movable frame, means including a movable part on the drive shaft, under the control of the operator, for causing said sleeve to be intermittently engaged by the disks on the drive shaft to cause it to be turned with the latter to raise the movable frame, and the same means similarly controlled to retard the movement of the sleeve as it is turned by the weight of the movable frame as it descends.

18. In a device of the class described, the combination of a stationary frame provided with a drive shaft thereon, a mold, a vertically movable frame provided with tamping members therein operable within the mold under the weight of the movable frame and its associated parts, means for operating the tamping members means on the drive shaft connected with the movable frame adapted to be intermittently turned with the former to raise the movable frame, means upon the drive shaft under the control of the operator for causing such intermittent engagement between the shaft and the raising means and the same means similarly controlled to release such engagement with the drive shaft to allow the movable frame to descend and to retard its downward movement.

19. In a device of the class described, the combination of a stationary frame, a drive shaft therein, a vertically movable frame, tamping members within the vertically movable frame, means for operating the tamping members and means for raising the movable frame comprising a drive shaft, a pair of disks upon the drive shaft, one fixed

and the other movable longitudinally thereof, a sleeve interposed between the disks on the drive shaft, a rope or chain connecting the sleeve with the movable frame, means under the control of the operator for shifting the movable disk to cause the sleeve to be engaged to turn with the shaft or to be released to allow it to descend by gravity, and the same means similarly controlled to retard the descent of the movable frame to cause it to descend at uniform speed.

20. In a device of the class described, the combination of a stationary frame, a mold fixed relatively thereto, a vertically movable frame carrying reciprocal tamping members therein, means for causing the tamping members to be reciprocated, means for raising the movable frame comprising an intermittently driven shaft in the stationary frame and means for driving the same, a pair of disks on the shaft, one fixed and the other longitudinally movable thereon, a collar fixed upon the shaft adjacent the movable disk, a sleeve interposed between said disks and normally loose upon said shaft and means for moving the movable disk to cause the sleeve to be engaged with the shaft whereby the movable frame will be raised and the same means operable to release the sleeve to allow the movable frame to descend and the same means similarly controlled for retarding its descent to cause it to descend at substantially uniform speed.

21. In a device of the class described, the combination of a stationary frame, a mold fixed relatively thereto, a vertically movable frame carrying reciprocal tamping members therein, means for causing the tamping members to be reciprocated, means for raising the movable frame comprising an intermittently driven shaft in the stationary frame and means for driving the same, a pair of disks on the shaft, one fixed and the other longitudinally movable thereon, a collar fixed upon the shaft adjacent the movable disk, a sleeve interposed between said disks and normally loose upon said shaft and means under the control of the operator operable between the collar and the movable disk for moving the movable disk to cause the sleeve to be engaged with the shaft whereby the movable frame will be raised and the same means similarly controlled operable to release the sleeve to allow the movable frame to descend and the same means for retarding its descent, to cause the movable frame to descend at substantially uniform speed and means similarly controlled operable through the movement of the movable frame to alternately cause the shaft to be engaged with and released from its driving connection.

22. In a device of the class described, the combination of a stationary frame, a mold fixed relatively thereto, a vertically movable

frame carrying reciprocal tamping members therein, means for causing the tamping members to be reciprocated, means for raising the movable frame comprising an intermittently driven shaft in the stationary frame and means for driving the same, a pair of disks on the shaft, one fixed and the other longitudinally movable thereon, a sleeve interposed between the disks and normally loose upon the shaft and means under the control of the operator adapted to slide the movable disk on the drive shaft to cause the sleeve to be engaged with the shaft whereby the movable frame will be raised and the same means similarly controlled to release the sleeve to allow the movable frame to descend, and frictionally retard its descent to cause it to descend at uniform speed.

23. In a device of the class described, the combination of a stationary frame, of a vertically movable frame supported therein, a drive shaft in the stationary frame and means for driving it, a cross shaft in the movable frame, a plurality of tamping bars pivotally connected with parts on the cross shaft of the movable frame to facilitate the vertical reciprocation of said tamping bars, means for operating the tamping members from the drive shaft simultaneously with the movement of the frame, means for raising and lowering the movable frame comprising a sleeve upon the drive shaft, a rope or chain connecting the sleeve with the movable frame, disks upon the drive shaft one fixed and the other adjustable thereon, and a wedge under the control of the operator adapted to adjust the movable disk on the drive shaft to cause it to alternately impinge the sleeve to cause the movable frame to be raised and then to release it to allow the movable frame to descend, and means controlled by the movement of the movable frame to disconnect the drive shaft from its driving source to limit the upward movement of the movable frame.

24. In a device of the class described, the combination of a stationary frame, of a vertically movable frame supported therein, a drive shaft in the stationary frame and means for driving it, a cross shaft in the movable frame, a plurality of tamping bars pivotally connected with parts on the cross shaft of the movable frame to facilitate the vertical reciprocation of said tamping bars, means for operating the tamping members from the drive shaft simultaneously with the movement of the frame comprising parts adjustably related to compensate for the changing position of the movable frame, means for raising and lowering the movable frame comprising a sleeve upon the drive shaft, a rope or chain connecting the sleeve with the movable frame, disks upon the drive shaft one fixed and the other adjustable thereon, and a wedge under the con-

- trol of the operator adapted to adjust the movable disk of the drive shaft to cause it to alternately impinge the sleeve to cause the movable frame to be raised and then to release it to allow the movable frame to descend, and means controlled by the movement of the movable frame to disconnect the drive shaft from its driving source to limit the upward movement of the movable frame.
25. In a machine of the class described, the combination of a stationary frame provided with a drive shaft therein, of a vertically movable frame supporting a cross shaft therein, provided with a plurality of eccentrics set at different angles relatively, a plurality of vertical tamping bars, yokes embracing the eccentrics and pivotally connected with the tamping bars, a filler section provided with an opening therethrough adapted to alternately register with a magazine discharge opening for receiving the discharged material, the said filler section being shiftable with relation to the magazine outlet to register with the opening in the top of the mold for discharging the charge received from the magazine into the mold, means for operating the tamping bars from the drive shaft, means for raising and lowering the movable frame comprising a sleeve on the drive shaft, a rope or chain connecting the sleeve with the movable frame, a pair of disks upon the drive shaft, one fixed and the other movable thereon and adjustable lengthwise thereof, a collar fixed on the shaft adjacent the movable disk, a wedge suitably supported to be moved, adapted to pass between said collar and movable disk to cause the latter to impinge the sleeve to cause it to be rotated with the shaft to raise the movable frame and to disengage said sleeve to permit the movable frame to descend, a constantly driven member, clutch mechanism interposed between the constantly driven member and the drive shaft adapted to intermittently engage and release said parts, and means controlled by the movement of the movable frame to operate said clutch mechanism to cause engagement and disengagement between the constantly driven member and the sleeve.
26. In a machine of the class described, a mold, a stationary frame, a vertically movable frame supported therein, tamping bars suitably supported in the movable frame, mechanism in said frame for reciprocating the tamping bars, a drive shaft in the stationary frame, means connecting said drive shaft with the mechanism for operating the tamping bars, means for raising the movable frame and releasing it to allow it to descend by force of gravity comprising a pair of disks on the drive shaft, one fixed and the other adjustable thereon, a sleeve interposed between said disks and a rope or chain connecting said sleeve with the movable frame, means under the control of the operator for causing intermittent frictional engagement and release of the disks of the drive shaft with the ends of the sleeve whereby the movable frame may be raised and the same means similarly controlled for retarding the gravity descent of the movable frame to cause it to descend at uniform speed.
27. In a machine of the class described, a mold, a stationary frame, a drive shaft supported therein, a movable frame carrying a cross shaft therein, a series of eccentrics upon said cross shaft set at different angles relatively, a plurality of vertical tamping bars, yokes embracing the eccentrics and pivotally connected with the tamping bars, a filler section provided with an opening therethrough adapted to alternately register with a magazine discharge opening for receiving the discharge of material, the said filler section being shiftable with relation to the magazine outlet to register with the opening in the top of the mold for discharging the charge received from the magazine into the mold, means for operating the tamping bars from the drive shaft, comprising parts adjustable relatively to compensate for the varying position of the vertically movable frame, means for raising and lowering the movable frame comprising a sleeve on the drive shaft, a rope or chain connecting the sleeve with the movable frame, a pair of disks upon the drive shaft, one fixed and the other feathered thereon and adjustable lengthwise thereof, a collar fixed on the shaft adjacent the movable disk,

a wedge suitably supported to be moved, adapted to pass between said collar and movable disk to cause the latter to impinge the sleeve to cause it to be rotated with the shaft to raise the movable frame and to disengage said sleeve to permit the movable frame to descend, a constantly driven member, clutch mechanism interposed between the constantly driven member and the drive shaft adapted to intermittently engage and release said parts, and means controlled by

the movement of the movable frame to operate said clutch mechanism to cause engagement and disengagement between the constantly driven member and the sleeve. 15

In testimony whereof I have affixed my signature, in presence of two witnesses.

GEORGE W. KRAMER.
